UNITED STATES PATENT OFFICE

ALEXANDER MCLEAN NICOLSON, OF NEW YORK, N. Y., ASSIGNOR, BY MESNE ASSIGNMENTS, TO FEDERAL TELEGRAPH COMPANY, A CORPORATION OF CALIFORNIA

ECCENTRIC DRIVE CONE LOUD SPEAKER

Application filed March 11, 1927. Serial No. 174,493.

This invention relates to sound reproducing and radiating apparatus and more particularly to such apparatus designated as "loud speakers" and comprising a relatively large rigid diaphragm exposed on one side at least to unconfined air and driven by mechanical vibrations corresponding to the sounds to be reproduced.

It is an object of this invention to provide an improved device of the class described, so arranged that a diaphragm having an apex symmetrically disposed with reference to its periphery, may be caused to vibrate in a different manner to that in which it would vibrate were the driving force impressed on its apex, whereby a different frequency response, and character of sound, may be obtained.

It is a further object of this invention to provide improved apparatus of the class described, so arranged as to have parts particularly adapted to respond to high frequencies and other parts particularly adapted to respond to low frequencies connected together in such a manner that the sound vibrations may be impressed between the said parts.

It is still a further object of my invention to provide generally improved apparatus of the class described.

The features of novelty which I believe to be characteristic of my invention are set forth with particularity in the appended claims. My invention itself, however, both as to its fundamental principles and as to its practical embodiments, will best be understood by reference to the specification and accompanying drawings in which:

Figures 1 and 2 are respectively front and side elevations of one form of my invention;

Figure 3 is a top plan view thereof;

Figure 4 is a top plan view partly in section of a modified form of my invention;

Figure 5 is a front elevation thereof, and

Figure 6 is a front elevation of a still further modified form of my invention.

In accordance with my invention, I provide a relatively large rigid diaphragm, having one side at least exposed to unconfined air. In one form of my invention, the diaphragm may be in the form of a large and rigid cone or as in another form thereof, it may be in a form having 2 cones of different sizes, having their apexes facing in opposite directions, and forming a circular line of intersection.

The driving force is applied to the diaphragm, not at the apex, as has heretofore been the custom in apparatus of the class, but at certain points on the diaphragm, whereby a different mode of vibration is established in the diaphragm. In case the driving force is applied to the apex, stress waves are developed in the material and spread outwardly from the apex at equal speeds in all directions. When the driving force is applied to a point other than the apex, stress waves are set up in the material and radiate from the point of application of the driving force, but in this instance, a part of the wave travels toward the apex instead of away from it, resulting in a substantially different mode of vibration of the diaphragm and a substantially different characteristic of the radiated sound. This is particularly true when the driving force is applied at a plurality of points and mechanically out of phase.

In accordance with a further modification of my invention, I apply the driving force at a plurality of points on the line of intersection formed by the two cones, either at a pair of points mechanically different, or are more than 2 points mechanically out of phase.

In this instance, the smaller cone is set into vibration by stress waves traveling from its periphery toward its apex, while the large cone is set into vibration by stress waves traveling toward its periphery from an imaginary apex.

Referring now more particularly to Figures 1, 2 and 3; 1 designates a relatively large conical diaphragm of suitable material, such as paper, cardboard, wood, composition or even metal, adapted to be supported by a suitable base 2, carrying a stress plate 3, to which is secured a piezo-electric device 4, such for example, as a crystal of Rochelle salt exhibiting the well known "hour glass" configuration. One basal plane of the crystal is suitably secured to the stress plate 3, as by bolting, or cementing by the use of Rochelle salt "melt", comprising Rochelle salt, from which the desired amount of water has been removed by heating it at a temperature above the melting point thereof. A second stress plate 5 may be secured to the top basal plane of the crystal 4, and is sufficiently long to extend outwardly on each side of the crystal so as to be capable of connection to the diaphragm 1, at points intermediate the apex of the periphery thereof. Suitable driving rods 6 and 7 are fastened to the stress plate 5 on one end and to points 8 and 9 on the diaphragm, at the other end, which points may be suitably reinforced as by the application of Rochelle salt "melt" to the diaphragm at these points.

A pair of electrodes 10 and 11, shown diagrammatically, are also provided for the purpose of impressing electrical oscillation at the crystal device 4. The precise form and arrangement of these electrodes is not, per se, part of this invention and any suitable arrangement may be utilized. For example, one of the electrodes 10 may constitute a belt of conducting material, forming a loop around the crystal, intermediate its basal planes, while the other electrode 11, may be an internal electrode or may be formed by the plates 3 and 5. The application of electrical oscillations to the electrodes 10 and 11, causes the development of stresses in the crystal which tend to rotate the stress plate 5 with respect to the stress plate 3.

The connection of the opposite ends of stress plate 5 to the diaphragm operates to set the same into vibration at points 8 and 9 with a vibration which is mechanically out of phase. The base 2, as will be understood, should be made to have a sufficiently large mass so that the stresses developed in the crystal will be transmitted to the atmosphere through vibrations of the diaphragm.

Referring now to Figures 4 and 5, I have shown the diaphragm as being made up of an incomplete cone 12, having its apex portion cut away, and an apex portion 13 having its periphery secured to the inner periphery of the cone 12 to form a circular line of the intersection 14. In this instance, the stress plate 5 is secured upon the horizontal diagonal of the circle of intersection 14, at points 15 and 16 thereon. It will be seen that vibrations are transmitted from these points outwardly to the periphery of the sectional

cone 12 and inwardly to the apex of the cone 13.

In the arrangement shown in Figure 6, the diaphragm is substantially the same but in this instance, the stress plate 3 is made sufficiently long so that the circle of intersection 14 may be attached at points 17 and 18 to stress plate 5, and at points 19 and 20 to stress plate 3.

While I have shown and described certain preferred embodiments of my invention, it will be apparent that modifications and changes may be made without departing from the spirit and scope of my invention as will be understood by those skilled in the art.

I claim:

1. A loud speaker comprising a relatively large conical shaped diaphragm exposed on one side to unconfined air, the center of said diaphragm being turned inwardly upon itself, and means for driving said diaphragm from points on opposite sides of the center thereof. 85
2. A loud speaker comprising a relatively large conical diaphragm, a central conical portion for said diaphragm extending in a direction opposite to the normal direction of said diaphragm, and means for driving said diaphragm from points on opposite sides of the center of said central conical portion. 90
3. A loud speaker comprising a relatively large conical diaphragm exposed on one side to unconfined air, an inner central conical portion extending from said diaphragm in a direction opposite to the normal direction of said diaphragm, and means for driving said diaphragm at points coincident with the juncture of said inner central conical portion and said diaphragm. 95
4. A loud speaker comprising a relatively large symmetrical diaphragm exposed on one side to unconfined air, and means for driving symmetrical points thereof in predetermined different phase relation. 105
5. A loud speaker comprising a relatively large conical diaphragm, a central conical portion extending from said diaphragm in a direction opposite to the normal direction of said diaphragm, and means for driving said diaphragm from points on the circumference of a circle defined by the intersection between said cone and the plane of intersection normal to the axis thereof between the conical diaphragm and the central conical portion thereof. 110
6. A loud speaker comprising a relatively large conical diaphragm having the apex thereof re-entrant into the body and means connected to said diaphragm at a plurality of points for actuating respective portions of said diaphragm out of time phase with each other. 115
7. A loud speaker comprising a relatively large conical diaphragm having the apex thereof formed re-entrant into the body, and 120

means for driving said diaphragm from points on the intersection between the outer surface and the inner re-entrant surface.

8. A sound reproducing device comprising
5 a diaphragm, piezo electric means for actuating said diaphragm and means connecting said piezo electric actuating means and said diaphragm at a plurality of points for actuating portions of said diaphragm out of
10 time phase with respect to each other.

Signed at New York city in the county of New York and State of New York this tenth day of March, A. D. 1927.
